UNITED STATES PATENT OFFICE

WALTER M. HANSON, OF GRAND RAPIDS, MICHIGAN, ASSIGNOR TO AMERICAN SEATING COMPANY, OF GRAND RAPIDS, MICHIGAN, A CORPORATION OF NEW JERSEY

SUPPORTING STANDARD FOR DESK TOPS

Application filed August 2, 1930. Serial No. 472,568.

The present invention relates to tables, desk tops for schools, and the like; and its object is to provide an improved rigid support for such structures and improved means 5 for mounting ink wells and the like in connection therewith.

This and any other and more specific objects including structural details and economies of production are attained by, and the 10 invention finds preferable embodiment in, the desk structure particularly described in the body of this specification and illustrated by the accompanying drawing, in which:—

15 Figure 1 is an elevational end view of a desk structure, such as are installed in schools and the like;

20 Figure 2 is a top plan view of a portion thereof, the table top being partially broken away;

25 Figure 3 is an elevational front view of a portion of said structure and a vertical sectional view of a portion of its support taken on line 3—3 of Figure 1;

Figure 4 is a vertical sectional view thereof taken on line 4—4 of Figure 1 and showing an inkwell in the background; and

30 Figure 5 is a vertical sectional view of the same taken on line 5—5 of Figure 1, the inkwell not being shown in section.

In this drawing a table or desk structure is illustrated having a table portion 1 and a supporting standard portion. This standard portion comprises a vertical post 3 provided with suitable legs 4 and a box designated generally 5 having a bottom wall 6, upwardly-diverging side walls 7, and front and rear end walls 9, 10, all these walls being rigidly joined together as by forming the

35 bottom and the side walls of a single piece of sheet metal bent as shown, and the end walls being connected therewith by their inwardly extending flanges 11 welded thereto.

40 The upper end of the post 3 extends through an opening 12 in the lower portion of the box, such opening being formed through its bottom wall 6 and partially in the side walls 7, and the post being desirably united with these parts as by welding.

These side walls have outwardly horizontally extending flanges 13 supporting and secured to the table portion 1 as by screws 14 passing through holes 15 in these flanges. The said flanges have depressed portions 16 65 in which is seated a horizontal plate 17, joined thereto as by welding, this plate having an opening 18 in which the upper end of the post extends fittingly, being desirably joined thereto as by welding. These flanges 60 13 have, as shown, other depressed portions 19 in which is seated another horizontal plate 20, similarly joined thereto, this plate having an opening 21 in which extends upwardly the neck 22 of an inkwell 23 seated in the 65 box and desirably having its sides 24 in contacting relation with the side walls 7 of the box.

These plates 17, 20 have, as shown, holes 15 through which fastening screws 14 for the table portion extend. The structure as shown also has a rear wall 25 secured to the box as by screws passing through holes 26 in the rear wall 10 of the box; and also has a shelf 27 held in place as by screws 28 passing 70 through holes in the bottom wall 6 of the box.

75 It will be seen that a peculiarly rigid support for the table portion is thus provided, the said bottom wall, end walls, horizontal plates and the post being rigidly connected, and the diverging relation of the side walls affording a bracing connection with the table portion; and that a stable support for the ink well is provided.

80 It will also be seen that the parts of this structure may be readily assembled and disassembled for storage and shipment.

85 Furthermore: a structure sufficiently rigid for most purposes is provided if one of the side walls 7 be omitted.

90 The invention being intended to be pointed out in the claims, is not to be limited to or by details of construction of the particular embodiment thereof illustrated by the drawing or hereinbefore described.

95 I claim:

1. In a supporting standard for a desk top and the like: a vertical post; a box having a bottom portion with an opening through which the upper end of the post fittingly ex- 100

tends, and upwardly-diverging side walls with horizontal flanges to which the desk top is fastened.

2. In a supporting standard for a desk top and the like: a vertical post; a box having a bottom portion with an opening through which the upper end of the post fittingly extends, upwardly-diverging side walls with horizontal flanges to which the desk top is fastened and end walls, all the walls being rigidly joined together.

3. In a supporting standard for a desk top and the like: a vertical post; a box having a bottom portion with an opening through which the upper end of the post fittingly extends, and upwardly-diverging side walls with depressed portions and horizontal flanges to which the desk top is fastened; a horizontal plate seated in said depressed portions and having an opening in which the upper end of the post extends fittingly.

4. In a supporting standard for a desk top and the like: a vertical post; a box having a bottom portion with an opening through which the upper end of the post fittingly extends, and upwardly-diverging side walls with depressed portions and horizontal flanges to which the desk top is fastened; a horizontal plate seated in said depressed portions and having an opening in which the upper end of the post extends fittingly, the plate being fastened to the side walls and to the desk top.

5. In a supporting standard for a desk top and the like having an opening to the herein-after-mentioned ink well: a vertical post; a box having a bottom portion with an opening through which the upper end of the post fittingly extends, and upwardly-diverging side walls with depressed portions and horizontal flanges to which the desk top is fastened; a horizontal plate seated in said depressed portions and having an opening; an ink well in the box having a neck extending through the opening in the plate.

6. In a supporting standard for a desk top and the like having an opening to the herein-after-mentioned ink well: a vertical post; a box having a bottom portion with an opening through which the upper end of the post fittingly extends, and upwardly-diverging side walls with depressed portions and horizontal flanges to which the desk top is fastened; a horizontal plate seated in said depressed portions and having an opening; an ink well in the box contacting its side walls and having a neck extending through the opening in the plate.

7. In a supporting standard for a desk top and the like having a rear wall and a shelf: a vertical post; a box having a bottom portion with an opening through which the upper end of the post fittingly extends, an end wall, and upwardly-diverging side walls having depressed portions and horizontal flanges; a

horizontal plate seated in said depressed portions and having an opening in which the upper end of the post extends fittingly, the walls and the plate being rigidly joined together, and said flanges, the end wall and said bottom portion having holes receiving fastening means for the desk top, said rear wall and said shelf respectively.

8. In a supporting standard for a desk top and the like: a vertical post; a box having a bottom portion with an opening through which the upper end of the post fittingly extends, and side walls having depressed portions in their upper edges; a horizontal plate seated in said depressed portions and having an opening in which the upper end of the post extends fittingly, said plate being fastened to the side walls and to the desk top between the side walls.

9. In a supporting standard for a desk top and the like: a vertical post; a member having a bottom portion with an opening through which the upper end of the post fittingly extends, an upwardly extending laterally-inclined portion secured adjacent its upper edge to said top, a horizontal upper portion having an opening in which the upper end of the post extends fittingly; and a horizontally disposed brace member secured to said bottom portion.

In testimony whereof I have hereunto set my hand at Grand Rapids, Michigan, this 30th day of July, 1930.

WALTER M. HANSON.
